CHARLES F. CUMMINS, OF SPOKANE, WASHINGTON, ASSIGNOR OF ONE-HALF TO
EDWARD JAMES, OF PLUMMER, IDAHO.

SNAP-HOOK.

1,282,049.

Specification of Letters Patent. Patented Oct. 22, 1918.

Application filed March 25, 1918. Serial No. 224,530.

To all whom it may concern:

Be it known that I, CHARLES F. CUMMINS, a citizen of the United States, residing at Spokane, in the county of Spokane and 5 State of Washington, have invented certain new and useful Improvements in Snap-Hooks, of which the following is a specification.

The present invention relates to improvements in snap hooks, and particularly to locking means therefor, to prevent opening of the locked hook.

The primary object of the invention is the provision of an efficient, inexpensive, but 15 simple device that is facile in operation, and durable in service, in the performance of its functions.

The invention consists essentially in certain novel combinations of a locking sleeve 20 slidable on the hook, as will be hereinafter more fully described and claimed.

In the accompanying drawings one complete example of the physical embodiment of the invention is illustrated, and a slight 25 modification thereof is also shown, constructed according to the best modes so far devised for the practical application of the principles of the invention.

Figure 1 is a top plan view of a snap hook 30 embodying this invention.

Fig. 2 is a side elevation of the hook of Fig. 1, with the slidable locking sleeve in section for convenience of illustration.

Fig. 3 is an enlarged, fragmentary view, 35 showing parts in section, of a modified form of the invention.

The invention is applicable for use in connection with the well known and standard types of snap hooks or trace hook and in the 40 drawings herewith the usual loop 1 and curved hook portion 2 are shown, the prong or lug 3 being provided at the curled or hooked end 2 of the device, and the elastic or resilient spring tongue 4 co-acts in customary manner with the hook end 3, lying 45 snugly up against the inner surface of the prong or lug when the hook is locked or snapped to an object, and by depressing the spring tongue the device is readily unhooked.

To prevent accidental displacement or de-

pression of the spring tongue, the slideable locking sleeve 5 is employed and surrounds the tongue, and the prong 3 when in locked position. The sleeve is slideable on the 55 tongue and is provided at one end with a knob or handle 6 by means of which it may be manipulated with facility in locking or unlocking the hook. A helical spring 7 of the protractile type surrounds the tongue 60 between the sleeve 5 and the shoulder 8 of the hook, and this spring normally holds the sleeve in hooked position, urging it against the shoulder 2^a at the base of the prong 3 of the hook, a cut out 5' being present in 65 the sleeve.

In the modified form shown in Fig. 2, the hook is designated 2' having the end prong 3' while the spring tongue 4' is slotted as at 4^a, and the sleeve 5^a engages against the 70 shoulder 2^a. A handle 6' is provided on the sleeve, and the spring 7' is located in the sleeve between the end wall 9 of a slot in the tongue and a turned in lug 10 forming part of the sleeve, the tendency of the 75 spring being to urge the sleeve against the shoulder 2^a of the hook.

When the snap hook is to be opened, in either form of the invention illustrated, the thumb is placed on the handle and the sleeve 80 withdrawn, the cut out 5' riding down on the prong 3 to guide the sleeve, and at the same time pressure is placed on the sleeve to depress the tongue 4, or 4^a as the case may be, and the hook may be snapped over 85 an object. The sleeve is then released and the spring returns the sleeve to locked position as the resiliency or elasticity of the tongue returns the tongue and sleeve to position in Fig. 2. The cut out 5' enables the 90 sleeve to slide or snap quickly over the point of the prong 3 or 3' and the parts are accurately guided to position. With the sleeve in the position indicated in the figures of drawing it will readily be evident that the 95 tongue is held securely locked against depression within the opening of the snap hook and cannot accidentally be displaced, but the sleeve may be unlocked with facility and despatch when desired to open the hook. 100

Claims—

1. The combination with a snap hook and

its spring tongue, of a slidable locking sleeve inclosing the tongue and the end of the hook, and a spring engaging the sleeve to hold it in locked position.

5 2. The combination with a snap hook and its spring tongue, of a slidable locking sleeve inclosing the tongue and the end of the hook,

said sleeve having a cut-out guide portion at one end to ride over the end of the hook, and a helical spring inclosing the spring 10 tongue and interposed between the sleeve and a fixed portion of the hook.

In testimony whereof I affix my signature.

CHARLES F. CUMMINS.
